UNITED STATES PATENT OFFICE.

JOEL CHENEY WELLS, OF SOUTHBIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

DESIGN FOR A LENS STRAP.

Application filed May 19, 1923. Serial No. 6,229. Term of patent 14 years.

To all whom it may concern:

Be it known that I, JOEL CHENEY WELLS, a citizen of the United States, residing at Southbridge, in the county of Worcester and State of Massachusetts, have invented a new and original ornamental Design for a Lens Strap, of which the following is a specification, reference being made to the accompanying drawings, forming a part thereof.

Figure 1 is a front elevation of a lens strap showing the new design.

Figure 2 is an end elevation of a lens strap of my new design, and

Figure 3 is a side plan view thereof.

Manufacturers, such as The American Optical Company, the assignee of this patent, make end pieces separate and distinct from the complete frame, enabling

opticians to repair spectacles. In manufacturing the lens strap as disclosed, it is preferably made of metal or such material as is susceptible to a highly polished surface, and since the strap has reflecting faces or facets, reflections of an ornamental nature are created, and these are very noticeably distinctive to the eye.

What I claim is:

The ornamental design for a lens strap, as shown.

In testimony whereof, I affix my signature in the presence of two witnesses.

JOEL CHENEY WELLS.

Witnesses:

SUSAN CASAZZA,
ESTHER M. LAFLER.
